UNITED STATES PATENT OFFICE.

JOSEPH E. BARRANGER, OF PHILADELPHIA, PENNSYLVANIA.

JAR-CLOSURE.

No. 922,240.

Specification of Letters Patent.

Patented May 18, 1908.

Application filed October 13, 1908. Serial No. 457,547.

To all whom it may concern:

Be it known that I, JOSEPH E. BARRANGER, a citizen of the United States, residing in Philadelphia, Pennsylvania, have invented certain Improvements in Jar-Closures, of which the following is a specification.

My invention relates to that particular class of closures for bottles, jars, tumblers, 10 or like receptacles, (hereinafter, for convenience, termed a "jar") which are known as "vacuum" closures, and in which the cap or cover is held in place upon the jar by the pressure of air thereupon, a vacuum or partial 15 vacuum having been established in the jar.

The object of my invention is to so construct a closure of this class that when the cap or cover is subjected to the pressure of 20 the air, and is forced downwardly thereby it will exert a properly applied compressing force upon the sealing gasket used in connection therewith and will have no tendency to distort said gasket or displace it from its 25 seat below the mouth of the jar.

In the accompanying drawing—Figure 1 is a vertical sectional view, on a much enlarged scale, of the upper portion of a jar constructed and provided with a sealing 30 gasket and cover in accordance with my invention, the parts occupying the positions assumed by them before the vacuum is established in the jar and the cover is subjected to the pressure of the air, and Fig. 2 35 is a similar view illustrating the relation of the parts to one another after the vacuum has been established, the cover subjected to the air pressure and the sealing of the jar effected.

In the drawing, 1 represents part of the body of the jar which has, on the outside of the same, immediately below the mouth, a vertical wall 2, terminating at its base in a beveled seat 3, and at the base of the latter 40 is a horizontal shoulder 4, and outwardly beyond the latter another vertical wall 5, at whose base is a second horizontal shoulder 6. In connection with the jar thus constructed I employ a sealing gasket 7 of 45 rhomboidal cross section and a cap 9 having an outer ring member 10 which presents an internal tapering, and preferably convex face 11 and a vertical base flange 12.

The rhomboidal sealing gasket is applied 50 to the jar so as to present two vertical faces and two outwardly and downwardly flaring

faces, the lower of the latter resting upon the beveled seat 3 of the jar and the inner vertical face bearing upon the vertical wall 2 above said beveled seat. When the cap 9 is first applied to the jar, therefore, the convex inner face of its ring member 10 bears upon the gasket at the junction of its outer vertical and upper beveled faces and when the downward pressure of the air is exerted upon the cap, the resultant of the pressure of the said convex face upon the gasket is substantially in the direction of the arrows x, Fig. 1, and the uniform compression and symmetrical expansion of the gasket is effected, the shoulder 4 overcoming any tendency of the cap to force the gasket downwardly from its seat on the jar, or to twist or distort it in such a way as to destroy its symmetrical cross section and thus cause leakage and the reduction in 75 the thickness of the upper and lower ends of the gasket permitting of the forcing of the same into the contracted spaces between the upper and lower vertical walls of the jar and the corresponding portions of the cap without offering undue resistance to the downward movement of the latter.

Contact of the lower edge of the vertical flange 12 of the ring member of the cap with the horizontal shoulder 6 on the jar serves to 85 arrest the descent of the cap when the proper degree of compression has been exerted upon the sealing gasket, and to level said cap, and insure a uniform pressure of the same upon all portions of the gasket.

I claim:

1. A jar provided externally and below its mouth with a vertical wall having, at its base, a beveled seat terminating in a projecting shoulder, and a vertical wall below said shoulder, in combination with a sealing gasket of rhomboidal cross section which, when applied to the jar, presents tapering upper and lower ends, the latter resting on the projecting shoulder, and a cap having a ring member with tapering internal face for bearing on the outer face of the sealing gasket, and portions above and below said face presenting, when the cap is depressed, contracted spaces between them and the vertical walls of the jar.

2. A jar provided externally and below its mouth with a vertical wall having, at its base, a beveled seat terminating in a projecting shoulder, and a vertical wall below said shoulder terminating in a lower projecting shoulder, in combination with a sealing gas-

ket of rhomboidal cross section which, when applied to the jar, presents tapering upper and lower ends, the latter resting on the projecting shoulder at the base of the seat, and a cap having a ring member with tapering internal face for bearing on the outer face of the sealing gasket, and portions above and below said face forming, when the cap is depressed, contracted spaces between them and the vertical walls of the jar, the lower shoul-

der on the latter serving by contact with the lower edge of the cap to limit the descent of the same.

In testimony whereof I have signed my name to this specification, in the presence of two subscribing witnesses.

JOSEPH E. BARRANGER.
